SEWING MACHINE

Charles F. Rubel, Chicago, Ill., assignor to Union
Special Machine Company, Chicago, Ill., a cor-
poration of Illinois

Application May 21, 1936, Serial No. 80,943

16 Claims. (Cl. 112—16)

This invention relates to sewing machines; and it has reference more particularly to what are known as "cup feed" sewing machines wherein the fabric edges which are to be united, are fed between a pair of tangentially-arranged intermittently-rotated wheels or cups and thereby advanced progressively relative to the seaming instrumentalities of the machine.

A sewing machine of the type specifically referred to is featured in U. S. Patent 2,043,711 granted to the present applicant and Anton Wyleta on June 9, 1936, the same having three thread manipulating instrumentalities, to wit, a longitudinally reciprocating needle, a looper with both oscillatory and needle following movements, and a spreader confined to oscillatory movement alone in cooperating with said needle and looper. The machine produces a two-thread overedge seam which is not altogether satisfactory for certain classes of work, for example, in seaming full fashioned hosiery and the like, due to its tendency to gap.

My invention is directed toward making possible the conversion of a cup feed sewing machine of the specifically indicated sort, for the production of three-thread overedge seams which are proof against gapping, without necessitating the aid of thread manipulating instrumentalities other than those already on the machine, and without requiring any changes whatever in the motion of said instrumentalities or in the construction and arrangement of the mechanism relied upon to actuate them.

The foregoing and other attendant advantages I attain as hereinafter more fully described, through a slight change in the instrumentality which heretofore functioned solely as a spreader whereby the same is adapted to perform in the added capacity of a looper for carrying and manipulating a third yarn; and by providing suitable facilities for guiding and tensioning this third yarn enroute to said instrumentality.

In the drawings,

Fig. I shows, in elevation, one side of a cup feed sewing machine conveniently embodying my invention.

Fig. II is a fragmentary view drawn to a larger scale and showing the machine in longitudinal section.

Fig. III is a fragmentary plan section along a staggered plane indicated approximately by the arrows III—III in Figs. I and II.

Figs. IV, V, VI and VII are fragmentary perspective views showing the positions assumed by the thread manipulating elements of my improved

cup feed sewing machine, incident to performance of one of the loop forming cycles.

The cup feed sewing machine herein illustrated is, generally speaking, like the one featured in the patent, supra, and, as shown, comprises a hollow housing in the form of a standard 1 with a lateral projection or head 2 at the top thereof. Suspended from the head 2 is a pair of tangentially-arranged, circumferentially-knurled feed wheels or cups 3 and 4, which are secured to the lower ends of vertical shafts 5 and 6 extending up into the hollow of said head. The shaft 5, see Fig. II, consists of two aligned sections 5a, 5b which are loose-coupled at 7, the upper section 5a being journaled in a fixed bushing 8 set into the head 2, and the lower section 5b journaled in a bracket bearing 9 fulcrumed at 10 so that the cup 3 can be swung outwardly away from the cup 4 to facilitate insertion of the fabric edges F and F' (Figs. III—VII) between them. Suitable spring means (not illustrated) influential upon the bearing bracket 9, serves to maintain the feed cup 3 in yielding engagement with the companion feed cup 4. The shaft 6 for the feed cup 4 is journaled in a fixed bearing 11 on the machine housing, and secured to its upper end within the head 2, is a spur gear wheel 12 which meshes with a similar spur gear wheel 13 at the top of the upper section 5a of the shaft 5 for the cup 3 so that the two cups are driven in unison. Intermittent rotation is imparted to the cups 3 and 4 through the medium of a rotary clutch device 15 on the shaft 6 actuated by a link rod 16 having an adjustable pivotal connection at 17 with an upright arm 18 on a rock shaft 19 journaled within the machine housing 1. Rocking movement is imparted to the shaft 19 by virtue of the co-ordination of a horizontal arm 20 thereon with the rod 21 of an eccentric strap 22 which embraces an eccentric (not shown) on a transverse drive shaft 23 whereof the opposite ends are journaled in oil tight bearings afforded by the side walls of the housing. The drive shaft 23 extends to the exterior of the housing 1 at the side of the machine shown in Fig. I, and has there secured to it a combined hand wheel and pulley 24 whereby the machine may be actuated either manually or under power. The needle 25 of the machine operates directly above the edges of the feed cups 3 and 4 at the region of tangency of the latter, and is fixed in the outer end of a reciprocating horizontal supporting member in the form of a bar 26 which is guided for axial or end-wise movement in an oil tight connection or bushing 27 set into the front wall 28 of the housing 55

1, see Figs. II and III. From Fig. III it will be observed that the feed cup shafts 5 and 6 are disposed in a vertical plane at an acute angle to the vertical plane through the path of movement 5 of the needle 25. At its inner end within the housing 1, the needle bar 26 is coupled, by means of a pitman 29 with an actuating crank 30 on the drive shaft 23 of the machine, see Fig. II. The usual thread carrying looper of the machine is 10 designated 31 and, as shown, is adjustably secured by a set screw 32, in a transverse aperture at the outer end of a supporting member or bar 33 which extends at a slight upward inclination to the horizontal into the interior of the housing 1. 15 From Fig. II it will be noted that the bar 33 is journaled, with capacity for combined axial and oscillatory movement, in oil tight bearing bushings 34 and 35 set respectively into the front and rear walls 28 and 36 of the housing 1. Oscilla- 20 tory movement is imparted to the looper bar 33 from the drive shaft 23 through an eccentric strap rod 37 whereof the upper end engages a pin 38 extending laterally from a block 39 which is secured to said bar within the housing in the 25 interval between the bushings 34 and 35. The bar 33 receives its endwise movements from another crank 40 on the drive shaft 23, said crank being connected by means of a pitman 41, with the lower end of a rocker arm 42 fulcrumed to 30 swing on the fixed center 43 and having its upper end in turn coupled, by means of a link 44, with the block 39 on the said bar. The other thread manipulating instrumentality 45 of the machine is confined solely to oscillatory motion 35 about the axis of another upwardly-inclined supporting member or bar 46 which extends substantially parallel to the looper rod 33 and to the outer end of which said instrumentality is secured. As shown in Fig. II, the bar 46 for the 40 instrumentality 45 is journaled in an elongated oil tight bushing 47 secured in the front wall 28 of the housing 1. Within the housing 1 a laterally extending pin 48 on the bar 46 connects with the upper end of an eccentric strap rod 49 which 45 is actuated by another eccentric (not shown) on the drive shaft 23.

The usual stitch tongue indicated at 50, over which the seam loops are formed, is supported directly above the needle 25 and in the plane of 50 tangency of the two feed cups 3 and 4 by an arm 51 at the bottom end of an adjustably-fixed bracket 52 pendant from the head 2 of the housing 1. The needle thread 53 is drawn from a suitable source of supply (not shown) through a 55 tension device 54 at the side of the machine remote from the observer in Fig. I, then passes under a fixed guide finger 55, then to a guide eye 56 on the needle bar 26 and finally to the eye of the needle 25. The looper thread 57, on the 60 other hand, first passes through a tension device 58 at the near side of the machine in Fig. I, then through a fixed guide eye 59, then to a spring take-up 60, then through another fixed guide eye 61, then to a guide eye 62 at the outer end of 65 the looper bar 33, and finally to the looper 31.

In order to convert a cup feed sewing machine such as described for the purposes of my invention, I slightly alter the form of the instrumentality 45 from that shown in the patent hereinbefore referred to, that is to say, I provide said instrumentality with eyes 63 and 64, respectively, at the toe and heel ends of its tongue portion 65, and with a connecting groove 66 between said eyes for passage of a third yarn 67, as well as with a 70 hook 68 at said heel for controlling the looper

thread 57. As a result of this change, the instrumentality 45 is made capable of performing in the added capacity of a supplemental thread-carrying looper in a manner presently explained. For purposes of distinction, the instrumentality 45 will be hereinafter referred to as the "supplemental looper". On its way to the supplemental looper 45 from a supply source (not shown) the additional thread 67 first passes through a tension device 69 positioned adjacent the tension device 58 for the looper thread 57 at the side of the machine pictured in Fig. I, then through a fixed guide eye 70, and then over a guide finger 71 (Figs. I and II) secured to the underside of the head 2 of the machine housing, and finally 15 through the guide eye 62 through which the thread 57 also passes as hereinbefore explained.

The loop forming cycle of the machine is as follows:

In Fig. IV the supplemental looper 45 has just 20 released a loop 72 of the looper thread 57 and is nearing the limit of its upward swing; while the looper 31 is swinging forward crosswise of the needle through the needle thread loop 73 and at the same time following the needle 25 which has already started on its retractive stroke. In Fig. V, the looper 31 has reached the limit of its forward swing, holding the needle thread loop 73 and still following the needle 25 but at a decelerating rate; while at the same time, the supplemental looper 45 is moving down immediately 25 behind said looper 31 and engaging the looper thread 57. In Fig. VI, the supplemental looper 45 has reached the limit of its downward swing crosswise of the needle 25, with the new loop 74 30 of the thread 57 arrested in its hook 68, and has positioned the thread 67 so that said needle can pass over it on its next advancing stroke. In Fig. VII, the looper 31 has just released the needle thread loop 73 and is nearing the limit of its 35 retractive swing, while the needle 25 is advancing over the thread 67 to hold the latter during the succeeding upward swing of the supplemental looper 45. The parts thereupon all return to the 40 position shown in Fig. IV for the initiation of the next loop forming cycle, which, of course, occurs 45 immediately after advance of the two fabric edges F, F' by the feed cups 3 and 4. During the functioning of the needle 25 and the thread manipulating instrumentalities 31 and 45 as just 50 explained, the seam loops are formed over the stitch finger 50 in a manner well known in the art.

Having thus described my invention, I claim:

1. In a sewing machine, a pair of feed cups for 55 advancing between them a number of fabric edges which are to be united; a reciprocating needle; a cooperating thread carrying looper for engaging the thread of the needle and drawing loops therefrom, said looper having oscillatory movement crosswise of the needle as well as bodily movement in the direction of the needle; and a supplemental thread-carrying looper confined to oscillatory movement crosswise of the needle to cooperate with said needle and the first 60 mentioned looper.

2. In a sewing machine, a pair of feed cups for 65 advancing between them a number of fabric edges which are to be united, a reciprocating needle; a cooperating thread carrying looper for 70 engaging the thread of the needle and drawing loops therefrom, said looper having oscillatory movement crosswise of the needle as well as bodily movement in the direction of the needle; and a supplemental thread-carrying looper hav- 75

- ing a tongue end to draw loops from the thread of the first mentioned looper, and a projection on said tongue to control the first looper thread loops.
5. 3. In a sewing machine, a pair of feed cups for advancing between them a number of fabric edges which are to be united; a reciprocating needle; a cooperating thread-carrying looper for engaging the thread of the needle and drawing loops therefrom, said looper having oscillatory movement crosswise of the needle as well as bodily movement in the direction of the needle; and a supplemental thread-carrying looper confined to oscillatory movement crosswise of the 10 needle, said supplemental looper having a tongue end to draw loops from the thread of the first mentioned looper, and a projection on said tongue to control the first looper thread loops.
4. In a sewing machine, a pair of feed cups for 20 advancing between them a number of fabric edges which are to be united; a reciprocating needle; a cooperating thread-carrying looper for drawing loops from the thread of the needle; a bar supporting the looper; means for oscillating the 25 bar to move the looper crosswise of the needle and for reciprocating it endwise to concurrently move the looper in the direction of the needle; a supplemental thread-carrying looper to draw loops from the thread of the first mentioned 30 looper; a supporting bar for the supplemental looper; and means for oscillating the last mentioned bar to move the supplemental looper crosswise of the needle in timed relation with the latter and the first looper.
35. 5. In a sewing machine, a pair of feed cups for advancing between them a number of fabric edges which are to be united; a reciprocating needle; a cooperating thread-carrying looper for drawing loops of the thread on the needle; a bar supporting the looper; means for oscillating the 40 bar to move the looper crosswise of the needle and for reciprocating it endwise to move the looper in the direction of the needle; a supplemental thread-carrying looper to engage 45 the thread of the first mentioned looper and to draw loops therefrom, said supplemental looper having a projection to control the first looper thread loops; a supporting bar for the supplemental looper; and means for oscillating the 50 last mentioned bar to move the supplemental looper crosswise of the needle in timed relation with the latter and said first looper.
6. In a sewing machine, a housing; a pair of 55 horizontally-arranged feed cups supported at an elevation by the housing for advancing between them a number of fabric edges which are to be united; a needle movable crosswise of the upper edges of the two feed cups in the region of their tangency; a horizontal needle bar extending 60 through a guide bearing into the interior of the housing; a thread-carrying looper for drawing needle thread loops from the needle; a bar supporting the looper and extending through a bearing into the interior of the housing; a supplemental 65 thread-carrying looper to take the thread of the first mentioned looper and draw loops therefrom; a bar carrying the supplemental looper and likewise extending into the housing; and mechanism within the housing operative to 70 effect, in timed relation, intermittent rotation of the feed cups, endwise reciprocation of the needle bar, combined oscillatory and endwise movement of the looper bar, and oscillatory movement alone of the supplemental bar.
75. 7. In a sewing machine, a housing; a pair of
- horizontally-arranged feed cups supported at an elevation by said housing for advancing between them a number of fabric edges which are to be united; a needle movable crosswise of the top edges of the two feed cups in the region of their tangency; a horizontal needle bar extending through a guide bearing into the interior of the housing; a thread-carrying looper for drawing needle thread loops from the needle; a bar supporting the looper and extending at an upward 10 inclination to the horizontal through a bearing into the interior of the housing; a supplemental thread-carrying looper to take the thread of the first mentioned looper and draw loops therefrom; a bar carrying the supplemental looper 15 and likewise extending at an upward inclination to the horizontal into the housing; and mechanism within said housing operative to effect, in timed relation, intermittent rotation of the said feed cups, endwise reciprocation of the needle bar, 20 combined oscillatory and endwise movement of the first looper bar, and oscillatory movement alone of the supplemental looper bar.
8. In a sewing machine, a housing with a laterally projecting head; a horizontally-reciprocating 25 needle bar and a needle carried thereby beneath said head; vertical shafts mounted in and depending from said head, the plane of said shafts being at an acute angle to the path of needle movement; wheels at the lower ends of said 30 shafts for feeding a number of fabric edges; and individual thread-carrying instrumentalities co-operating with said needle in forming a three thread overedge seam to unite the fabric edges.
9. In a sewing machine, a housing having a 35 laterally-projecting head; a horizontally-reciprocating needle bar and a needle carried by said bar beneath the head; vertical shafts mounted in and depending from said head, the axes of 40 said shafts being in a plane at an acute angle to the path of needle movement; feed wheels at the lower ends of said shafts for feeding a number of fabric edges; a thread carrying looper; means supporting said looper for oscillation into and out of the needle thread loops and 45 for movement laterally to a position over the fabric edges; and a supplemental thread carrying looper; cooperating with the first mentioned looper and the needle in the formation of a three thread overedge seam. 50
10. In a sewing machine, a housing with a laterally-projecting head; a pair of feed cups suspended from the head for advancing between them a number of fabric edges which are to be united; a needle movable crosswise of the top 55 edges of the two feed cups in the region of their tangency; a horizontal needle-supporting bar extending through a guide bearing into the interior of the housing; a thread-carrying looper for drawing needle thread loops from the needle; a bar supporting the looper and extending through a bearing into the interior of the housing; a supplemental thread-carrying looper to take the 60 thread of the first mentioned looper and draw loops therefrom; a bar carrying the supplemental looper and likewise extending into the housing; and mechanism within said housing operative to effect, in timed relation, intermittent rotation of the feed cups, endwise reciprocation of the needle bar, combined oscillatory and endwise movement of the first looper bar, and oscillatory movement alone of the supplemental looper bar. 65
11. In a sewing machine, a housing with a laterally-projecting head at its top; a pair of feed cups suspended from the head for advanc- 70

ing between them a number of fabric edges which are to be united; a needle movable crosswise of the top edges of the two feed cups in the region of their tangency; a horizontal needle bar extending through a guide bearing into the interior of the housing; a thread-carrying looper for drawing needle thread loops from the needle; a bar supporting the looper and extending at an upward inclination to the horizontal through a bearing into the interior of the housing; a supplemental thread-carrying looper to take the thread of the first mentioned looper and draw loops therefrom; a bar carrying the supplemental looper and likewise extending at an upward inclination to the horizontal into the housing; and mechanism within the housing operative to effect in timed relation, intermittent rotation of the feed cups, endwise reciprocation of the needle bar, combined oscillatory and endwise movement of the first looper bar, and oscillatory movement alone of the supplemental looper bar.

12. A sewing machine for forming a three thread overedge seam, comprising a drive shaft; feed wheels for supporting and advancing a number of fabric edges in a vertical plane; a needle; a bar carrying said needle and extending from a point adjacent the feed wheels to a point adjacent said drive shaft; means operated by said drive shaft for reciprocating said needle bar; a looper; a looper bar mounted for oscillation and endwise movement on a fixed axis and extending from a position adjacent the feed wheel to a position adjacent said shaft; means operated by the shaft for oscillating the looper bar and for moving it endwise; a supplemental thread-carrying looper cooperating with the first mentioned looper and the needle; a bar supporting said supplemental thread-carrying looper mounted for oscillation about a fixed axis extending from a point adjacent the feed wheels to a point adjacent said shaft; and means operated by said shaft for oscillating the last mentioned bar.

13. In a sewing machine, opposed feed wheels for supporting and advancing a number of fabric edges in a vertical plane; a needle and means for imparting endwise movement thereto; a looper and means for oscillating it about a fixed axis and for reciprocating it in the line of said axis whereby said looper is moved in the direction of feed as well as transversely thereof from a position above one of the feed wheels to a position above the other feed wheel; and a supplemental thread-carrying looper cooperating with

the first mentioned looper and said needle in forming a three thread overedge seam about the fabric edges.

14. In a sewing machine a closed housing; means exteriorly of the housing for feeding a number of fabric edges; a thread-carrying needle and a plurality of cooperative individual thread-carrying instrumentalities also exteriorly of the housing for forming an over-edge uniting seam wherein individual loops of the threads of the cooperative instrumentalities are concatenated with each other and with the needle thread loops; supporting members for said needle and said instrumentalities respectively confined to movement in fixed axial lines and extending through oil tight connections into the interior of the housing; and mechanism within the housing for actuating said supporting members.

15. In a sewing machine, a closed housing; means exteriorly of the housing for feeding a number of fabric edges; a thread-carrying needle and a pair of cooperative individual thread-carrying instrumentalities also exteriorly of the housing for forming a three-thread over-edge uniting seam wherein individual loops of the threads of the two cooperative instrumentalities are concatenated with each other and with the needle thread loops; individual supporting members for said needle and said instrumentalities requiring only rotary or longitudinal reciprocatory motion to effect loop formation; oil tight connections where said instrumentalities penetrate a wall of the housing; and mechanism within the housing for actuating the supporting members as aforesaid.

16. In a sewing machine, a closed housing; feed wheels exteriorly of the housing for supporting and advancing a number of fabric edges; a thread-carrying needle and a pair of cooperating individual thread-carrying instrumentalities also exteriorly of the housing and above the feed wheels for forming a three-thread over-edge uniting seam wherein individual loops of the threads of the two cooperative instrumentalities are concatenated with each other and with the needle thread loops; actuating mechanism within the housing; and individual bars or shafts respectively confined to movement in fixed axial lines and having oil tight connections with a wall of the housing whereby the necessary movements are communicated from the actuating mechanism to the feed wheels, the needle and the cooperative instrumentalities aforesaid.

CHARLES F. RUBEL.
